(57) **CLAIM**

The ornamental design for a inflatable Kwanzaa candles and candelabra, as shown and described.

DESCRIPTION

FIG. 1 is a front view of the candles & candleabrum showing my new design.

FIG. 2 is a rear view thereof;

FIG. 3 is a left side view thereof;

FIG. 4 is a right side view thereof; and

FIG. 5 is a top view thereof; and,

FIG. 6 is a bottom view thereof and is flat and unornamented.

The candles are distinct in color. The middle candle is black, the three candles on the left are red and the three candles on the right are green. The candleabrum color is terra cotta.
